UNITED STATES PATENT OFFICE.

WILLIAM M. JENKINS, OF CHICAGO, ILLINOIS.

WALL BOARD.

Application filed August 1, 1921. Serial No. 488,749.

This invention relates in general to wall boards, or, as they are frequently termed "plaster boards", adapted for use in building constructions wherein the boards are secured usually by nails to studding or cross stringers, to form upright walls and ceilings to which the plaster is applied. Wall boards of this general type now in use customarily comprise a composition body composed of gypsum, wood, or other fibre, mixed with water, and a drier, which hastens the setting of the gypsum. This body is customarily mixed to a plastic condition, rolled to a thickness of not less than three-eighths of an inch, and enclosed in a paper sheathing or envelope, the marginal edges of which are overlapped adjacent one edge of the board. The edges of these boards are customarily more or less rounded, due to the fact that in applying the paper covering the plastic composition of the body when the paper is drawn taut, naturally assumes a curved contour at the edges. Furthermore, the overlap or line of juncture of the edges of the paper envelope being disposed adjacent one edge of the board, results in a tendency of the outer edge of the paper to become loosened and torn as the result of handling of the boards. This loosening not only detracts from the smoothness of the boards, but actually weakens them along the edges where the nails are driven through and where the board should be strongest, and as the result, the boards frequently crack and break out at the edges when they are being nailed in position.

One of the primary purposes of my present invention is to provide a wall board, having a composition body and a paper covering, in which the overlap of the margins of the paper will be disposed intermediate the edges of the board instead of at one edge thereof, so that both edges of the body will be completely enclosed and will not be weakened by a loose edge of paper, and furthermore, by positioning the overlap at the center instead of at the edge of the board, the liability of the overlapping margin of paper becoming loose and torn is very materially reduced. To further obviate against loosening of this overlapping edge of the covering, my invention contemplates the application of an adhesive to the inner face of this margin by which the margin is secured and bound in position.

Another purpose of my invention is to

strengthen the body structure of the board by incorporating in the body composition thereof, suitable metal reinforcements, which add to the strength and rigidity of the board and materially reduce the liability of cracking resulting from the driving of nails through the board.

Still another object is to produce angular corners at the edges of the board so that adjacent boards will lie close together and form a relatively tight and smooth joint, as distinguished from the rough and somewhat open joint necessarily resulting from the round-edged boards heretofore employed.

Another feature of my invention resides in reinforcing the edges of the board by applying to the edges of the composition body during the construction thereof, and before the paper wrapper is applied, a reinforcement of suitable character, which not only strengthens the board at this point, but also contributes toward the formation of even angular corners.

Still another purpose of the invention is to provide a board with laminated edges through which nails may be driven to secure the board in place without danger of cracking, splitting or injuring the margins of the board.

Other objects and many of the inherent advantages of my invention will be readily appreciated as the same becomes better understood, by reference to the following description, when considered in connection with the accompanying drawings.

Referring to the drawings:

Fig. 1 is a perspective view on a small scale of a wall board embodying my invention;

Figs. 2 to 8 inclusive are cross-sectional views showing the various features of my invention individually embodied in a wall board; and

Fig. 9 is a similar view of a board with various features of my invention embodied therein.

Referring now to the drawings more in detail, reference character 11 designates the body of my improved board which is formed of composition, having as its principal ingredient gypsum, which is mixed with fibrous material, water, and suitable hardening material to form a plastic mass, commonly known as "stucco". In the manufacture of the board, this plastic stucco mass

is formed into a flat body or sheet, which by reason of the construction of my improved board, may be materially thinner than the boards now in customary use, which 5 are substantially three-eighths of an inch thick. By suitable machinery, this mass is laid upon a traveling sheet of paper, which, by a suitable mechanism, is folded over around the stucco mass which is simultaneously shaped to the proper form and dimensions, the paper being adapted to provide the covering or envelope 12 completely surrounding and enclosing the top, bottom, and side edges of the board.

15 Instead of overlapping the margins of the paper envelope at or adjacent to one edge of the board, as is customary, the paper sheet is so arranged and manipulated during the manufacture of my improved board, that the 20 joint formed by the overlapping of the outer margin 13 upon the inner margin 14, is disposed intermediate the side edges of the board. When the joint is so disposed, the edges of the board are not weakened by a 25 joint in the envelope, and furthermore, the customary tendency of the outer overlapping margin of the envelope to curl back and become torn and broken, is obviated, since in the handling of the boards, the centrally disposed joint is not subject to becoming torn and injured as it is when exposed at the edge of the board. The edges of the 30 board, therefore, are smooth and fully enclosed in the envelope, and are considerably 35 stronger than the edges of the boards in which the envelope joint occurs at the margin of the board. In order to further insure a tight joint between the overlapping paper edges, I prefer to apply an adhesive between 40 these overlapping margins, which binds them securely in position. The adhesive may be applied either to the outer face of the inner margin or the inner face of the outer margin, as preferred, during the manufacture of the 45 board.

Instead of joining the overlapped margins of the paper covering by an adhesive, as above suggested, it may in some instances be preferable to employ the plastic material 50 of the body itself as the binder between these edges, and in such cases, the inner margin 14 is, during the manufacture of the board, depressed into the body of the material, as shown in Fig. 3, and some of the 55 plastic material is forced over the outer face of said margin and between the margins 13 and 14, so that this material itself serves as a binder to lock said overlapped edges together.

60 While the board may be made without reinforcement, as disclosed in Fig. 1, it is nevertheless preferable in many instances, to strengthen the board by reinforcing the composition body. One form of reinforcement 65 shown in Fig. 2 consists of a series of lon-

gitudinally extending reinforcing members 15 in the shape of wires or rods of the required dimensions, which may be imbedded in any desired position in the body, but for purposes of illustration, are shown as disposed adjacent the top and bottom faces thereof.

In Fig. 4, another form of reinforcement consisting of a wire mesh fabric 16, is shown, and in this instance, two plies of such mesh 70 are imbedded in the body, one adjacent the upper, and the other adjacent the lower face of the board. These reinforcements materially strengthen the body and prevent it from cracking or chipping when nails are 75 driven through, particularly near the edges of the board.

In Fig. 5, a similar wire mesh reinforcement 80 17 is shown, but in this instance, instead of being disposed adjacent the faces of the board, it is positioned substantially in the center thereof midway between the faces, where it performs a similar function to the double reinforcement shown in Fig. 4, and since only one half the amount of reinforcement 85 is utilized in this instance, the cost of production of the board is consequently less.

In order to strengthen the board at the edges, I may position at each edge of the body a longitudinally extending reinforcing strip 18, as shown in Fig. 6, which may be made of fibrous material, or even of metal, if preferred. These strips, in addition to 90 strengthening the board, serve to insure angular junctures at the corners of the board 95 between the side edges and the top and bottom. Such angular corners are desirable and much preferable to the customary rounded corners, since when the boards are laid close together, edge to edge, a close fitting smooth joint is secured instead of the rough depressed joint which necessarily ensues from the use of round-edged boards.

While in Figs. 1 to 6 previously described, 100 I have shown the corners of the board as rectangular, it may be desirable in some instances to have the side edges inclined with respect to the plane of the top and bottom faces, as shown in Fig. 7, wherein the side edges 19 and 21 are shown converging. This angularity of the edges with respect to the planes of the board faces permits a slightly overlapped joint when two boards are placed edge to edge, but when constructed 105 as shown in Fig. 7, obviously in order to insure the overlapping joint, alternate boards must be laid with their bottoms outwardly. Should it be preferable to have all of the 110 envelope joints formed by the overlapping margins 13 and 14 disposed inwardly, then the side edges of the boards may be parallel 115 instead of converging, but still disposed at an angle to the faces of the board.

In order to provide a board which will 120 possess a maximum of strength along its 125

edges, and one which will not chip, crack, or in any wise become injured by the driving of nails therethrough adjacent the edges, my invention contemplates a board having laminated edges, as shown in Fig. 8. These edges are composed of a plurality of plies 22 of preferably fibrous material, which may be laid in contiguous relation, as shown, or they may be slightly separated with a space 10 between filled with the composition of the body. In order to insure an interlock between these laminated edges and the body of the board, one or more of the plies or laminations are extended into the body, and for 15 purposes of illustration, I have shown the top and bottom plies so extended, and bonded with the composition body of the board.

While any one or more of the various features above described may be embodied in 20 any board, I have shown in Fig. 9, a board in which the various features are combined to provide an extremely strong and durable structure. In this board, the composition body 11 is reinforced not only with the wire 25 or rod reinforcement 15, but also with the centrally disposed wire mesh reinforcement 17. The edges of the board are formed of laminations 22 interlocked and bonded with the composition body, and the extreme edges 30 are further strengthened by the longitudinally extending reinforcing strips 18. These strips are disposed obliquely with respect to the faces of the board, thus permitting the attainment of the overlapping joints between 35 adjacent boards, as previously explained. The whole structure is surrounded and enclosed in the envelope 12, the marginal edges 13 and 14 of which form a joint intermediate the side edges of the board possessing the 40 advantages heretofore mentioned.

It is believed that my invention, its construction, and advantages will be understood from the foregoing without further description, and it should be manifest that the 45 structural details may be varied within considerable limits without exceeding the scope of the invention, as defined in the following claims.

I claim:

50 1. A wall board, comprising a composition body, reenforcing means disposed along an edge of said body, and covering material surrounding said body including the reenforced edge thereof.

55 2. A wall board, comprising a composition body, a sheath enclosing the same, and reenforcing means extending along an edge of said body within said sheath.

60 3. A wall board, comprising a body reenforced at the edges thereof, and a sheath

enclosing said body including said reenforced edges.

4. A wall board, comprising a composition body, means for reinforcing the longitudinal edges of said body, and a sheet of 65 covering material surrounding said body and reinforcing means.

5. A wall board, comprising a composition body, reinforcing strips extending longitudinally of the body at the edges thereof, 70 and a one piece sheet of covering material enclosing said body and said strips.

6. A wall board, comprising a composition body having reinforced edges inclined with respect to the plane of said board, and 75 a sheet of covering material surrounding said body and having its edges overlapped remote from the edges of the board.

7. A wall board, comprising a composition body provided with laminated edges, 80 and a covering enclosing said body.

8. A wall board, comprising a composition body reinforced at each edge with laminations and enclosed in a sheet of covering material. 85

9. A wall board, comprising a body formed of composition and provided at its edges with laminated sheets interlocked with said composition, and a paper covering surrounding said body. 90

10. A wall board, comprising a composition body provided with laminated margins, reinforcing members at the edges of said margins, and a sheet of covering material enclosing said body. 95

11. A wall board, comprising a composition body, reenforcing strips extending along an edge of the body, and a sheet of covering material enclosing said reinforced edge.

12. A wall board, comprising a composition body having reenforced beveled edges, and an envelope of covering material surrounding said body.

13. A wall board, comprising a flat composition body provided with a laminated reinforced margin joined to the composition by a tongue and groove connection. 105

14. A wall board, comprising a flat composition body, covering material disposed over the flat faces thereof, and reenforcing strips extending longitudinally of the body and dove-tailed to the composition to provide a reinforced margin for the board. 110

15. A wall board, comprising a composition body provided with a laminated edge and a reinforcing element inclosing said edge and extending over said body beyond the inner edge of the laminæ. 115
